(57) **CLAIM**

The ornamental design for a tray, as shown and described.

DESCRIPTION

FIG. 1 is a top perspective showing my new design of a tray thereof;

FIG. 2 is a bottom perspective view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front-side elevational view thereof;

FIG. 8 is a back-side elevational view thereof;

FIG. 9 is a cross section view thereof along section lines 9-9 in FIG. 3 to more clearly bring out elements of the claimed design;

FIG. 10 is a cross section view thereof along 9-9 in FIG. 3;

FIG. 11 is a cross section view thereof along 9-9 in FIG. 3;

FIG. 12 is a cross section view thereof along 9-9 in FIG. 3; and,

FIG. 13 is a cross section view thereof along 9-9 in FIG. 3. The broken lines are for illustrative purposes only and form no part of the claimed design. Section lines in FIG. 3 are for illustrative purposes only and form no part of the claimed design.
